UNITED STATES PATENT OFFICE.

HARRY M. WELLS, OF BRIDGEPORT, CONNECTICUT, ASSIGNOR TO THE LOCOMOBILE COMPANY OF AMERICA, OF NEW YORK, N. Y.

DESIGN FOR A SOCKET-PIECE FOR AUTOMOBILE-FRAMES.

SPECIFICATION forming part of Design No. 34,071, dated February 12, 1901.

Application filed January 12, 1901. Serial No. 43,076. Term of patent 14 years.

To all whom it may concern:

Be it known that I, HARRY M. WELLS, of Bridgeport, in the county of Fairfield and State of Connecticut, have invented and produced a new and original Design for a Socket-Piece for Automobile-Frames, of which the following is a specification.

This invention relates to socket-pieces to be embodied in the under frames of automobile vehicles; and it consists in the design formed by the novel conformation of such socket-pieces, as hereinafter explained.

My design is illustrated in the accompanying drawings, in which—

Figures 1 and 2 are perspective views showing opposite ends of the socket-piece, and Fig. 3 is a longitudinal section therethrough on line 3 3 of Fig. 1.

The distinguishing feature of my design is a flaring or cup-shaped base 1 and three branches 2 2, projecting therefrom and merging close to the base 1, the ends of all of said branches presenting an open or tubular appearance.

I claim—

The design for a socket-piece for automobile-frames, substantially as herein shown and described.

In testimony whereof I have affixed my signature in presence of two witnesses.

HARRY M. WELLS.

Witnesses:

A. M. WOOSTER,
W. J. BENNETT.
